CLAIM

The ornamental design for a tab for a container lid, as shown and described.

DESCRIPTION

FIG. 1 is a top perspective view of a tab for a container lid showing our new design;

FIG. 2 is a top plan view thereof;

FIG. 3 is a front elevational view thereof;

FIG. 4 is a left side elevational view thereof;

FIG. 5 is a right side elevational view thereof; and,

FIG. 6 is a rear elevational view thereof.

The phantom lining shown in the drawing is for illustrative purposes only and forms no part of the claimed design.
